(57) CLAIM

The ornamental design for a key holder, as shown and described.

DESCRIPTION

FIG. 1 is a front perspective view of a key holder showing my new design;

FIG. 2 is a front perspective view thereof, shown without the environmental matter;

FIG. 3 is a front elevational view thereof;

FIG. 4 is a right side elevational view thereof, the opposite side being a mirror image;

FIG. 5 is a rear elevational view thereof; and,

FIG. 6 is a top plan view thereof.

The dotted line representation on FIG. 1 is for information only and forms no part of the subject design.

In the form of the invention shown, the major portion of the spherical key cord retainer is lined for silver color while the circular button is lined for yellow color.
